UNITED STATES PATENT OFFICE.

ALPHEUS W. ALTORFER, OF ROANOKE, ILLINOIS.

DRIVING MECHANISM.

1,269,573.

Specification of Letters Patent. Patented June 18, 1918.

Application filed February 16, 1914. Serial No. 818,887.

To all whom it may concern:

Be it known that I, ALPHEUS W. ALTORFER, a citizen of the United States, residing at Roanoke, in the county of Woodford and 5 State of Illinois, have invented certain new and useful Improvements in Driving Mechanism, of which the following is a specification.

This invention has reference to the driving mechanism for a washing machine, and includes means adapted to be actuated by the raising of the lid or cover of the machine for disconnecting said driving mechanism and thereby bring the dolly, or agitating 10 means, or other clothes washing elements operated by the driving mechanism, to a standstill.

The invention has for a further object to provide a driving mechanism for a washing 20 machine, including suitable gearing arranged to be operated by an electric motor or from any other suitable source of power and to transmit motion to the dolly, agitating means, or other clothes washing elements, and means is provided for disconnecting 25 said driving mechanism so as to bring the dolly, agitating means, or other clothes washing elements to a standstill when the lid or cover of the machine is raised; and 30 said parts are returned to their normal or operative positions when said lid or cover is returned to its closed position.

In the drawings:

Figure 1 is an end elevation showing a 35 washing machine with my invention applied thereto, parts being broken away to illustrate the meshing of the teeth of a reciprocating rack with the teeth of a pinion;

Fig. 2 is a side elevation of Fig. 1, a part 40 being removed but shown in dotted lines;

Fig. 3 is a fragmentary plan view of Fig. 2, parts being removed and other parts being broken away;

Fig. 4 is a detail plan showing a modification included in the driving mechanism;

Fig. 5 is a detail plan of a part of the driving mechanism, and means carried by the lid or cover of the machine arranged to disconnect the gearing in the driving mechanism, when the lid or cover of the machine is raised, and to reconnect said gearing when the lid or cover is closed;

Fig. 6 is an elevation in section of the parts shown in Fig. 5, as the same would appear on the line 6—6 of Fig. 5;

Fig. 7 is an elevation of Fig. 5 looking in the direction of the arrow shown on Fig. 5:

Fig. 8 is an end elevation of Fig. 5, somewhat similar to Fig. 6 showing parts partially raised, which position, they would 60 assume during the raising of the lid or cover of the machine;

Fig. 9 is a side view of Fig. 8 looking at the left hand side of said figure;

Fig. 10 is a plan view of Fig. 8 looking at 65 said parts in the direction of the arrow in said figure;

Fig. 11 is a view similar to Fig. 5, except that the modified construction in Fig. 4 is shown in said figure; 70

Fig. 12 is a perspective view of the casing or element attached to the lid or cover of the machine which is adapted to disconnect the gearing when the lid or cover of the machine is raised. 75

Like characters of reference denote corresponding parts throughout the figures.

1 designates a washing machine supported by a stand, platform or other suitable support, 2. The washing machine 1 has the 80 usual hinged cover or lid 3 through which operates a vertically disposed shaft 4, said shaft beneath the lid 3 supporting a dolly mechanism, or agitating mechanism, or other clothes washing elements 5, best seen 85 in dotted lines in Fig. 1.

On the upper end of the shaft 4 is carried a bevel pinion 6 said bevel pinion meshes constantly with a bevel pinion 7 carried on the inner end of a horizontally disposed 90 crossed shaft 8, having a bearing in a sleeve 9, and said shaft 8 on its opposite or outer end carries a bevel pinion 10, adapted to have a meshing relation with a bevel pinion 11 on a horizontally disposed shaft 12 which 95 is arranged transversely to the shaft 8. The sleeve 9 forming a bearing for the shaft 8 is preferably cast integral with a bracket 13 which is secured to the lid or cover 3 and also provided with bearing arms 14 through 100 which the shaft 12 passes and on which said bracket 13 and said lid or cover 3 may swing when said lid or cover is raised or lowered. The shaft 12 is further journaled in bearings 15 and 16 secured to the washing machine proper or some support fixedly attached thereto. 105

The shaft 12 is adapted to be rocked in its bearings and in turn impart a rocking movement to the cross shaft 8, which in turn, 110

will impart a rocking movement to the vertical shaft 4 in the washing machine. I accomplish this rocking movement by the use of the following elements: On the outer end 5 of the shaft 12 is carried a spur pinion 17 and the teeth of this pinion have a meshing relation with the teeth of a rack bar 18, said rack bar having movement in a sleeve or casing 19 which guides the movement of 10 said rack bar and maintains a meshing relation between said bar and the pinion 17, and said rack bar is connected with a pitman 18^a having a swiveled connection with a pin 20 on a gear wheel 21. The rotation 15 of said gear wheel 21 will reciprocate the pitman 18^a and with it the rack bar 18 in the sleeve or casing 19 and thereby rock the shafts 12, 8 and 4.

The sleeve or casing 19 is made in two 20 sections, see Fig. 2, to adapt it for attachment and to inclose the pinion 17 and the rack bar 18, and said sleeve or casing 18 is arranged to inclose the pinion 17, see Figs. 1 and 2 and is pivotally supported on the 25 shaft 12 so that it may oscillate and adapt itself to the movement of the pitman 18^a as it is operated by the gear wheel 21.

The gear wheel 21 is carried on a longitudinally disposed shaft 22 suitably journaled on the frame support or washing machine proper and said gear wheel 21 is operated by a pinion 23 on a short shaft 24; said short shaft 24 also carrying a pulley 25 engaged by a belt 26 operated from a 30 pulley 27 on the motor shaft 28. In this instance the motor is shown as an electric motor although the shaft 22 carrying the gear wheel 21 may be operated from a gasolene engine or from any other suitable 35 source of power. If an electric motor is used it will be suitably supported on the framework of the machine, as shown.

The gear wheel 21 may be partially incased by a casing 29 and the bevel gears 6 40 and 7 which are used to impart movement from the cross shaft 8 to the vertical shaft 4 in the washing machine, may be incased by a suitable casing 30.

The shaft 22 in addition to being employed for imparting movement to the shafts 12, 8 and 4 may also be employed for imparting movement to the wringer 31 through a vertically disposed shaft 32, suitably geared to the shaft 22. As no claim 50 is made to the wringer drive, these parts have only been illustrated in a rather indefinite way.

In the preferred construction shown in all figures except Figs. 4 and 11, the bevel pinion 11 on the shafts 12 is carried by a sleeve 33 which has a spline and groove connection with said shaft so as to adapt it to be rotated with the shaft and to slide on the shaft whereby, the bevel pinion 11 may be 60 moved out of and into mesh with the bevel

pinion 10 on the cross shaft 8. Said sleeve 33 is formed with an annular groove 34 in which operates a finger 35 pivotally secured to the top of the washing machine 1 or some fixed part thereof. 36 denotes a casing 70 adapted to be secured to the bracket 13 and with it to the lid or cover 3 of the machine, and said casing 36 is formed with parts 37 and 38 adapted to cover the pinions 10 and 11 as well as the sleeve 33. The part 37 of the casing 36 is formed with a groove 39, the opposite walls of which are curved, as best seen in Figs. 5 and 10, and when said casing 36 is secured in position on the machine, the walls of the groove 39 lie upon 80 opposite sides of the finger 35, entering the groove 34 in the sleeve 33. The shape of the opposite walls of said groove 39 are such that when the lid or cover 3 is raised said finger 35 will be oscillated in a positive 85 manner to move the sleeve 33 on the shaft 12 in a direction which will separate or disconnect the bevel pinions 11 and 10, and thereby bring the cross shaft 8 and shaft 4 to a standstill. When the lid or cover is 90 lowered or closed, the finger 35 moving in the groove 39 will move the sleeve 33 in the opposite direction and cause the bevel pinion 11 to be moved into meshing relation with the pinion 10. In this way one wall 95 of the groove 39 in the casing 36 will positively actuate the finger 35 and with it the sleeve 33 to disconnect the pinion 11 from the pinion 10, and the opposite wall of said groove will positively actuate the finger 35 100 to move it and the sleeve 33 in the opposite direction to bring the bevel pinion 11 in meshing relation with the bevel pinion 10.

In Figs. 4 and 11 the bevel pinion 11 on the shaft 12 is loosely carried in a suitable way on said shaft and has a clutch extension 11^a adapted to have connection with a clutch extension of the sleeve 33^a, said sleeve 33^a being somewhat similar to the sleeve 33 and formed with an annular groove 34^a in which operates the finger 35. In this construction, means is provided for positively moving the finger 35 and with it the sleeve 33^a to separate the clutch extension of said sleeve 33^a from the clutch extension 11^a of the 115 pinion 11, when the lid or cover 3 is raised, and a yielding means is employed for causing the sleeve 33^a to be brought into clutch engaging relation with the clutch extension 11^a of the pinion 11, when the lid or cover 120 is lowered or closed. In this modification the casing 36 does not have the groove 39, but it does have a sinuous shaped wall 40 which will bear against the finger 35 as the lid or cover 3 is raised for oscillating said finger and moving the sleeve 33^a to separate its clutch part from the clutch extension 11^a of the pinion 11. Bearing against one end of the sleeve 33^a is a spring 41 coiled 125 about the shaft 12, which also bears against 130

a collar 42 suitably spaced from the end of the sleeve 33^a and fixed on the shaft 12. As the sleeve 33^a is moved to separate its clutch part from the clutch extension 11^a of the 5 pinion 11, the spring 41 will compress, and when the lid or cover 3 is lowered or closed, returning the casing 36 to the position shown in Fig. 11, the spring 41 will act to return the sleeve 33^a to its normal position with its 10 clutch part engaging the clutch extension 11^a of the pinion 11 and cause said pinion 11 and said pinion 10 to rotate with the rotation of the shaft 12.

Suitably located on the machine, preferably 15 on the shaft 12 is a plate stop 43, against which the lid or cover 3 will rest when in its raised position.

What I claim is:—

1. In a driving mechanism, in combination, a machine having a hinged element, a shaft passing through said element, a cross-shaft journaled on said element and geared to said first shaft, a driving shaft journaled on said machine, meshing gears on said cross 20 and driving shafts, said gear on the driving shaft being slidable on said driving shaft to be moved into and out of meshing relation with said gear on the cross shaft, and means movable with said hinged element for 25 30 sliding said gear on the driving shaft.

2. In a driving mechanism, in combination, a machine having a hinged element, a shaft passing through said element, a cross-shaft journaled on said element and geared to said first shaft, a driving shaft journaled on said machine, meshing gears on said cross and driving shafts, said gear on the driving shaft having an extended sleeve provided with an annular groove, and said sleeve and 35 its gear being slidable on said driving shaft to move said gear into and out of meshing relation with the gear on the cross shaft, a pivoted member operating in the groove of said sleeve, and means attached to said 40 45 hinged element arranged to operate said pivoted member and slide said sleeve when said hinged element is moved.

3. In a driving mechanism, in combination, a machine having a hinged element, a shaft passing through said element, a cross-shaft journaled on said element and geared to said first shaft, a driving shaft journaled on said machine, bevel gears connecting said shafts, one of said gears being slidably 50 55 mounted whereby it may be moved into and out of meshing relation with the other gear, and means movable with said hinged element for sliding said slidable gear.

4. In a driving mechanism, in combination, a machine having a hinged element, a shaft passing through said element, a cross-shaft journaled on said element and geared to said first shaft, a driving shaft journaled on said machine, bevel gears connecting said 60 65 shafts, one of said gears being slidably

mounted whereby it may be moved into and out of meshing relation with the other gear, means for sliding said slidable gear, and means attached to said hinged element for operating said sliding means when said element is moved. 70

5. In a driving mechanism, in combination, a machine having a hinged element, a shaft passing through said element, a cross-shaft journaled on said element and geared 75 to said first shaft, a driving shaft journaled on said machine, meshing gears on said cross and driving shafts, said gear on the driving shaft being slidable, whereby it may be moved into and out of meshing relation with said gear on the cross-shaft, means carried by said hinged element for sliding said slid- 80 able gear when said element is moved, a gear wheel on one end of said driving shaft, a rack-bar for actuating said gear wheel, and means for reciprocating said rack-bar. 85

6. In a driving mechanism, in combination, a machine having a hinged element, a shaft passing through said element, a cross-shaft journaled on said element and geared 90 to said first shaft, a driving shaft journaled on said machine, bevel gears connecting said shafts, one of said gears being slidably mounted whereby it may be moved into and out of meshing relation with the other gear, 95 means movable with said hinged element for sliding said slidable gear, a gear wheel on one end of the driving shaft, a rack-bar for actuating said gear wheel, and means for reciprocating said rack-bar. 100

7. In a driving mechanism, in combination, a machine having a hinged element, a shaft passing through said element, a cross-shaft journaled on said element and geared to said first shaft, a driving shaft journaled 105 on said machine, bevel gears connecting said driving and cross-shafts, said gear on the driving shaft being slidable thereon, a pivoted member for sliding said slidable gear, a casing attached to said element and adapted to cover the gears connecting the 110 driving and cross-shafts, said casing provided with a groove to receive said pivoted member, the opposite walls of which are curved, whereby, when said element is raised, 115 one wall of the groove will move said pivoted member to slide the slidable gear in one direction, and when said element is lowered, the opposite wall of said groove will move said pivoted member to slide the slidable gear in the opposite direction. 120

8. In a driving mechanism, in combination, a machine having a hinged element, a shaft passing through said element, a cross-shaft journaled on said element and geared 125 to said first shaft, a drive shaft journaled on said machine, bevel gears connecting said driving and cross-shafts, said gear on the driving shaft being slidable thereon, a pivoted member for sliding said slidable gear, a 130

5 casing attached to said element and adapted to cover the gears connecting the driving and cross-shafts, said casing provided with a groove to receive said pivoted member, the 10 opposite walls of which are curved, whereby, when said element is raised, one wall of the groove will move said pivoted member to slide the slidable gear in one direction, and when said element is lowered, the opposite 15 wall of said groove will move said pivoted member to slide the slidable gear in the opposite direction, and reciprocatory rotary means for imparting movement to said driving shaft.

15 9. In a driving mechanism, in combination, a machine having a hinged element, a shaft passing through said element, a cross-shaft journaled on said element and geared to said first shaft, a gear wheel on the opposite end of said cross-shaft, a driving shaft, a sleeve slidably carried on said driving shaft, a gear wheel carried by said sleeve and adapted to mesh with the gear wheel on the end of the cross-shaft, a hinge for the 25 element having a bearing on the driving shaft, means for rocking said driving shaft, a pivoted member for sliding said sleeve and its gear wheel on the driving shaft, and a member attached to said element and adapted to operate said pivoted member, when said hinged element is moved.

10 10. In a driving mechanism, in combination, a machine having a hinged element, a shaft passing through said element, a cross-shaft journaled on said element and geared to said first mentioned shaft, a driving shaft journaled on said machine, gears on each of said driving and cross-shafts, adapted to intermesh to impart movement from the driving shaft to the cross-shaft, means controlling the operation of the gear on the driving shaft by said shaft, said means operating to actuate the gear on the driving shaft when the hinged element is lowered, whereby operation may be imparted to the cross-shaft, and said means operating to interrupt the operation of the gear on the driving shaft when the hinged element is raised.

11. In a device of the character described, 50 in combination, a hinged element, a shaft supported thereby, a driving shaft, driving connections between said shafts, a movable element on the driving shaft adapted to control the operation of the first mentioned shaft from the driving shaft, said element on the driving shaft being moved by the raising of the hinged element.

12. In a device of the character described, 55 in combination, a hinged element, a shaft supported thereby, a driving shaft, driving connections between said shafts, a movable

element on the driving shaft adapted to control the operation of the first mentioned shaft from the driving shaft, a finger for moving the element on the driving shaft, and means having a sinuous portion against which the finger rides, when the hinged element is swung. 65

13. In a device of the character described, in combination, a hinged element, a shaft supported thereby, a driving shaft, driving connections between said shafts, a movable element on the driving shaft adapted to control the operation of the first mentioned shaft from the driving shaft, a member for moving said element on the driving shaft, and means operated by the hinged element when swung, for actuating said member. 70

14. In a device of the character described, in combination, a hinged element, a shaft supported thereby, a driving shaft, driving connections between said shafts, a movable element on the driving shaft adapted to control the operation of the first mentioned shaft from the driving shaft, a member for moving said element on the driving shaft, means operated by the hinged element when swung, for actuating said member, and a rack-bar for operating said driving shaft. 75

15. In a device of the character described, in combination, a hinged element, a shaft supported thereby, a second shaft also supported by said hinged element, driving connections between said shaft, a driving shaft, driving connections between the driving shaft and said second mentioned shaft, a movable element on one of said last mentioned shafts adapted to control the transmission of movement one to the other, a member for moving said movable element, and means operated by the hinged element when swung, for actuating said member. 80

16. In a device of the character described, in combination, a hinged element, a shaft supported thereby, a second shaft also supported by said hinged element, bevel gears connecting said shafts, a driving shaft, driving connections between the driving and second mentioned shafts, means controlling the operation of said second mentioned shaft from said driving shaft, a pinion on the outer end of said driving shaft, a rack-bar in mesh with said pinion, a gear wheel connected with one end of said rack-bar, a motor, and driving connections between said motor and said last mentioned gear wheel. 85

In testimony whereof I affix my signature in presence of two witnesses.

ALPHEUS W. ALTORFER.
